SEQUENTIAL STARTING OF INDEPENDENT FREE PISTON ENGINES

Robert Huber, Bellevue, France, assignor to Societe d'Etudes & de Participations Eau, Gaz, Electricite, Energie, S. A., Geneva, Switzerland, a society of Switzerland

Application June 6, 1949, Serial No. 97,466
In France June 16, 1948

3 Claims. (Cl. 60—14)

1

The present invention relates to starting control devices for plants including at least two free piston machines each of which is provided with at least one starting cylinder into which is introduced, at the time of starting, a certain amount of gas under pressure, in particular of air under pressure, this introduction taking place as a result of the opening of a valve which is controlled through pneumatic means and which will be hereinafter called "starting valves."

Its object is to provide starting control devices for plants of the kind in question which are better adapted to meet the requirements of practice than those used up to this time, in particular which ensure in a particularly simple manner the starting of at least two free piston machines with a predetermined phase difference between them.

My invention consists chiefly in controlling the respective pneumatic means for opening the starting valves of at least two free piston machines through a common operating member and in differentiating the rates of flow and/or the masses of the respective gas streams which are to be set in movement in said pneumatic means for opening the corresponding starting valves, so as to produce a lag between the opening of one valve and that of the other, this lag when the number of free piston machines controlled by the same operating member is equal to two, being chosen equal to about one half of the period of reciprocation or oscillation of the free pistons or to an odd multiple of this value.

Preferred embodiments of the present invention will be hereinafter described with reference to the accompanying drawing, given merely by way of example and in which:

Fig. 1 diagrammatically shows a plant including two free piston machines and fitted with a starting control device according to my invention;

Fig. 2 shows another embodiment of such a starting control device;

Fig. 3 shows another embodiment.

In the following description, my invention will be supposed to be applied to the case of a plant including two free piston auto-generators, of practically the same dimensions and a receiver machine, for instance a turbine supplied with the motor gases delivered by these auto-generators.

Concerning auto-generators A and B, they are made, with the exception of their starting control devices, of any suitable construction, for instance as shown by Fig. 1, where each of these

2

auto-generators includes a motor cylinder 1, working preferably on the two-stroke cycle and on the diesel engine principle, which means that the fuel injected by an injector 2 is ignited by the heat of compression of the combustible agent compressed, during the inward stroke, by the motor piston 3 working in the motor cylinder 1. Motor cylinder 1 is fitted with at least one inlet port 4 and one exhaust port 5, both controlled by motor piston 3. This motor piston 3 is rigid with a compressor piston 6, these two pistons 3 and 6 constituting a movable unit. Furthermore, motor cylinder 1 is made rigid with a compressor cylinder 7 fitted with an inlet valve 8 and a discharge valve 9 and in which cylinder said compressor piston 6 is running. Around motor cylinder 1 there is provided a casing 10 which serves to receive the air compressed by the inner face of compressor piston 6 and which communicates with the inside of motor cylinder 1 when piston 3 is in a position close to its outer dead center position and clears inlet port 4.

In order to ensure the return stroke of the movable unit 3—6 of each of the auto-generators 25 A and B—that is to say the stroke during which the mass of air imprisoned in motor cylinder 1 is compressed to reach a temperature sufficient for producing ignition of the fuel injected by means of injector 2 and in the course of which the air present in the inner part of compressor cylinder 7 is compressed and delivered into casing 10—I make use of supplementary air cushions which, in the auto-generators shown by Fig. 1, are each imprisoned between the outer face of a compressor piston 6 and the end wall 7a of the corresponding compressor cylinder 7. These cushions store up most of the energy developed in motor cylinder 1 during the outward stroke of movable unit 3—6, to restore this energy to movable unit 3—6 during the inward stroke.

40 The free piston machines are started by introducing, into each of the spaces provided for these air cushions, a certain amount of air which expands to drive the corresponding free piston unit 3—6 toward its inner dead center position, so as thus to compress the air present in motor cylinder 1 and to ignite the amount of fuel injected at the end of this inward stroke.

45 For this purpose, I provide, in the end wall 7a of each of the compressor cylinders 7, an aperture 11 which is controlled by a valve 12, which constitutes the above mentioned starting valve. This starting valve 12 is located in a chamber or reservoir 13 provided on the outer face of the end wall 7a of compressor cylinder 7 and fitted, at its outer end, with a cylinder 14 in

which runs a piston 15 rigid with valve 12. This valve is subjected to the action of a spring 16 which tends to keep it closed. I provide, between the two chambers located respectively on opposite sides of piston 15, a conduit 17 fitted with a check valve 18 opening toward chamber 13, which conduit 17 may extend through piston 15 itself.

In order to start the machine, it suffices to fill up chamber 13 with air at a sufficiently high pressure and then quickly to open starting valve 12 so that the mass of air imprisoned in chamber 13 quickly enters the space between the outer face of compressor piston 6 and the end wall 7a of the compressor cylinder.

For this purpose, I provide an air conduit 19 opening into one end of cylinder 14. The air under pressure supplied through this conduit passes through conduit 17, into chamber 13. Once chamber 13 is filled, conduit 19 is placed in communication with the atmosphere, so that the air present on the outer side of piston 15 can escape to the atmosphere. The pressure acting upon the inner face of piston 15 can thus open starting valve 12, against the action of spring 16 and the air present in chamber 13 on the inner side of piston 15 starts the free piston unit into operation. The starting valve 12 is thus controlled through pneumatic means.

In the case of a plant including at least one group of two auto-generators A and B, it is advantageous, on the one hand, to connect together, by means of a communication conduit 20, the two casings 10 of the two auto-generators A and B and, on the other hand, to connect with a common conduit 21 the exhaust ports 5 of the motor cylinders of these two auto-generators, while managing so that the movable units of the two auto-generators A and B work with a phase difference equal to about one half of the period of reciprocation of their movable units, which means that, when the movable unit of one of these generators is in its inner dead center position, the movable unit of the other generator is in its outer dead center position.

With such arrangement, it is possible to reduce the dimensions of the casing 10 of each of these auto-generators and to steady the flow of the motor gases through conduit 21 toward a receiver machine, for instance a gas turbine 22.

In order to maintain this phase difference between auto-generators A and B during their operation, I may have recourse to any suitable device 23, in particular to one of those described in my U. S. Patent No. 2,473,204.

In order to obtain this phase difference as soon as the plant is started, according to the main feature of my invention, the pneumatic control devices of the starting valves 12 of auto-generators A and B are controlled by a common control member 24 and I provide means capable of differentiating either the rate of flow or the mass, or again both the rate of flow and the mass of the gas streams which are made to escape to the atmosphere to operate pneumatic means 13-14-15 so that one of the starting valve opens with a certain lag with respect to the other, this lag being chosen equal to about one half of the period of reciprocation of the free pistons or to an odd multiple of this value.

In order to differentiate the flow rates of the masses of air which, in cylinders 14, act upon the outer faces of pistons 15 and are made to escape to the atmosphere through control member 24 and conduit 24a, I may give different values either to the respective lengths of condu-

duits 19 or to the cross sections of at least portions of these conduits, or again to both the lengths and the sections of these conduits. Thus, in the embodiment of Fig. 1, the conduit 19 which connects control member 24 with the starting chamber 13 of auto-generator B is provided with a check valve 25 opening toward the cylinder 14 of this auto-generator and short-circuited by a by-pass conduit 26 of reduced cross section which slows down the flow of air from this cylinder whereas the conduit 19 corresponding to auto-generator A is free from any such slowing down means.

It should further be noted that the same control member 24 serves, in the plant illustrated by Fig. 1, to the filling up of chambers 13 with starting air. In order to obtain this, it suffices to bring the handle 27 of member 24 into the position shown by Fig. 1, so as to connect the two chambers 13 of generators A and B with a compressed air tank 28, the flow of air being not interfered with by check valve 25, which opens in the direction from tank 28 toward the chamber 13 of generator B.

In order to obtain starting, the handle 27 of control member 24 is brought into the position shown in dot-and-dash lines, which brings conduits 19 into communication with the atmosphere. The outflow of the air present on the external faces of pistons 15 is quicker for generator A than for generator B, the difference in rate of flow being chosen such that once control member has been brought into the position shown by Fig. 1, the valve 12 of generator A opens before the valve 12 of generator B, the lag between these openings being about equal to one half of the period of reciprocation of the free pistons, which is substantially the same for machines A and B. In this way, the mere pivoting of member 24 causes first generator A to start and then, after a time interval equal to half a period, generator B, whereby the operations of these two generators are given, from the start, the desired phase difference between them.

Another embodiment of my invention, according to which the desired phase difference is also obtained by giving different rates of flow to the air streams the outflow of which permits the opening of the starting valves, is shown by Fig. 2 which represents a starting device particularly advantageous in the case of two generators or other free piston machines disposed in line with each other. In this figure, I have shown only the portions of these two auto-generators in the end walls 7a of which are provided starting valves 12 analogous to the starting valves of the embodiment of Fig. 1. When control member 24 is in the position shown by Fig. 2, starting air flows from reservoir 28 past check valves 29, into starting air chambers 13 and past check valves 30 into cylinders 14 which contain the pistons 15, each of which is rigid with one of the starting valves 12.

The outflow of air present in cylinders 14, which causes valves 12 to open, takes place, according to Fig. 2, under the effect of the opening of a valve 31 kept in the closed position as long as control member 24 is in the position shown by Fig. 2, in which the pressure of the starting air acts upon the external face of a piston 32 rigid with said valve 31. If, on the contrary, control member 24 is rotated through 90°, so that conduit 33, through which starting air was fed to the starting device, is now in communication with the atmosphere through conduit 34, valve 31

opens under the influence of the pressure of the air imprisoned in cylinders 14 and which acts through openings 35a and 35b on the external face of piston 32 rigid with valve 31. As the cross section of opening 35a is greater than that of opening 35b, the air present in the cylinder 14 which corresponds to opening 35a escapes at a higher rate past valve 31 than the air present in the cylinder 14 provided with opening 35b. Consequently, the starting valve 12 of the auto-generator located on the left hand side of Fig. 2 opens before the starting valve 12 of the auto-generator located on the right hand side of Fig. 2, the cross sections of openings 35a and 35b being chosen in such manner as to give this phase difference a suitable value as above mentioned.

It should be noted that it may be advantageous, in a plant in which the casings of the two machines A and B communicate together, to charge the chamber 13 of the starting device of machine B, which starts after the other machine A, up to a slightly higher pressure, in order to make allowance for the overpressure that is produced during the first stroke of the first generator. I may obtain such a difference of pressure between the two chambers for instance by loading the two valves 17 and 29 by means of springs 29a (Fig. 2) exerting slightly different forces, the spring 29a of the starting device of the machine that is to start first being slightly stronger and consequently producing a slightly higher difference of pressure between conduit 33 and the chamber 13 of this first starting machine than the spring 29a interposed between the conduit 33 and the chamber 13 of the second starting machine.

In both of the embodiments above described, the interval between the times of starting of the two free piston machines is a consequence of the difference between the rates of flow with which air under pressure escapes from cylinders 14. However, as already above stated, this phase difference might also be obtained by an arrangement of the pneumatic devices which control starting such that the masses of air which are to escape to cause the starting valves to open are different. This difference between the air masses may be obtained by a different choice of the return forces of springs 16, this difference having for its effect to start the free piston machine which has the stronger spring after the other free piston machine. An analogous effect might be obtained by filling the cylinder 14 of one of the two generators with a mass of air having a pressure higher than that of the air present in the cylinder 14 of the other generator.

In the embodiment illustrated by Fig. 3, one of the cylinders 14 (the one on the right hand side of the drawing) has its portion on the outer side of piston 15 greater than the other cylinder, so that the mass of air which is to flow out to open one of the starting valves is greater than that corresponding to the other valve.

In all cases, the antagonistic force or air pressure difference is chosen in such manner as to obtain a phase difference between the beginning of the starting periods of the two auto-generators equal to the value above indicated.

Of course, I may also differentiate both the rate of flow and the mass of the air that is to be set into movement for opening the starting valve of each of the machines to be started.

In the preceding description, I have more especially referred to groups of two free piston machines to be started with a phase difference 75

equal to one half of the period of oscillation of the movable unit of these machines or an odd multiple of this value. Of course, my invention is not limited to the case where the number of free piston machines to be started with a predetermined phase difference from a common control member is equal to two.

Furthermore, it should be noted that free piston machines, for practical purposes, are generally provided with opposed pistons and not simple pistons such as shown by Fig. 1 for the sake of simplicity.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. In combination with a plant including at least two free piston machines, a starting control device which comprises, in combination, a compressed air reservoir for starting one of said machines, a starting valve for placing said machine in communication with said reservoir, a cylinder opening at one end into said reservoir, a piston movable in said cylinder forming a movable partition between said reservoir and the chamber of said cylinder located on the other side of said piston from said reservoir, said piston being operatively connected with said starting valve to open it when the pressure in said cylinder chamber drops to substantially atmospheric pressure, a compressed air reservoir for starting the other machine, a starting valve for placing said second mentioned machine in communication with said last mentioned reservoir, a cylinder opening at one end into said second mentioned reservoir, a piston movable in said last mentioned cylinder forming a movable partition between said last mentioned reservoir and the chamber of said last mentioned cylinder located on the other side of said last mentioned piston from said last mentioned reservoir, said last mentioned piston being operatively connected with said last mentioned starting valve to open it when the pressure in the said last mentioned cylinder chamber drops to substantially atmospheric pressure, means for filling each of said cylinders with gas under pressure, a common cylinder including a cylindrical wall and two end walls, a piston slidable in said third mentioned cylinder, this last mentioned cylindrical wall being provided with two ports located both on the same side of this last mentioned piston, these two ports being of different sizes and communicating with said two cylinder chambers respectively, a valve rigidly connected with the last mentioned piston mounted in the end wall of said third mentioned cylinder located on the same side of said last mentioned piston as said two ports, whereby said two ports are connected with the atmosphere when this last mentioned valve is open, a conduit opening into the chamber of said third mentioned cylinder located on the other side of said last mentioned piston from said two ports, a source of gas under pressure, and control valve means for connecting said last mentioned conduit either with said source or with the atmosphere.
2. In combination with a plant including at

least two free piston machines, a starting control device which comprises, in combination, a compressed air reservoir for starting one of said machines, a starting valve for placing said machine in communication with said reservoir, a cylinder opening at one end into said reservoir, a piston movable in said cylinder forming a movable partition between said reservoir and the chamber of said cylinder located on the other side of said piston from said reservoir, said piston being operatively connected with said starting valve to open it when the pressure in said cylinder chamber drops to substantially atmospheric pressure, a compressed air reservoir for starting the other machine, a starting valve for placing said second mentioned machine in communication with said last mentioned reservoir, a cylinder opening at one end into said second mentioned reservoir, a piston movable in said last mentioned cylinder forming a movable partition between said last mentioned reservoir and the chamber of said last mentioned cylinder located on the other side of said last mentioned piston from said last mentioned reservoir, said last mentioned piston being operatively connected with said last mentioned starting valve to open it when the pressure in the said last mentioned cylinder chamber drops to substantially atmospheric pressure, a common cylinder including a cylindrical wall and two end walls, a piston slideable in said third mentioned cylinder, this last mentioned cylindrical wall being provided with two ports located both on the same side of this last mentioned piston, these two ports being of different sizes and communicating with said two cylinder chambers respectively, a valve rigidly connected with the last mentioned piston mounted in the end wall of said third mentioned cylinder located on the same side of said last mentioned piston as said 40

two ports, whereby said two ports are connected with the atmosphere when this last mentioned valve is open, a conduit opening into the chamber of said third mentioned cylinder located on the other side of said last mentioned piston from said two ports, means forming passages between said conduit and each of the two first mentioned cylinder chambers respectively, check valves in said passages respectively opening toward said two first mentioned cylinder chambers, a source of gas under pressure, and control valve means for connecting said last mentioned conduit either with said source or with the atmosphere.

3. A starting control device according to claim 2 further including means forming passages between said conduit and each of said reservoirs, and check valves in said last mentioned passages respectively opening toward said reservoirs.
